ALBERT H. TAYLOR AND LEO C. YOUNG, OF WASHINGTON, DISTRICT OF COLUMBIA,
ASSIGNORS, BY MESNE ASSIGNMENTS, TO WIRED RADIO, INC., OF NEW YORK, N. Y., A
CORPORATION OF DELAWARE

REDUCTION OF FADING EFFECTS IN RADIO COMMUNICATION

Application filed July 28, 1928. Serial No. 295,968.

Our invention relates broadly to radio receiving apparatus and more particularly to a system for reducing fading effects in radio communication.

One of the objects of our invention is to provide a receiving system which automatically compensates for fading effects maintaining signal strength at the receiver substantially constant.

19 Another object of our invention is to provide an arrangement of superheterodyne circuits which cooperatively act to receive and reproduce signals independent of fading effects.

15 Other and further objects of our invention reside in the superheterodyne circuit arrangements and proportion of the circuits as set forth more particularly in the specification hereinafter following by reference to the 20 accompanying drawings in which:

Figure 1 is a diagrammatic view showing the arrangement of the superheterodyne apparatus at the receiver; Fig. 2 is a diagrammatic circuit arrangement of the two superheterodyne circuit arrangements of our invention; and Fig. 3 shows the details of the wiring of the apparatus in accordance with our invention.

In Letters Patent No. 1,669,218, issued May 30 8, 1928, to Albert H. Taylor, it has been pointed out that fading usually occurs at different time intervals on antennas which are separated more than $\frac{1}{4}$ of a wave length from the center of one exposure to the center 35 of the other, or which run in different directions so as to be differently influenced by different states of polarization in the changing wave front. A system of using two receivers with a common heterodyne is described in the aforesaid Letters Patent. That system had the disadvantage that the resulting audio frequency signal from one receiver could not be directly combined with the signal from the other receiver without vector 40 addition of the signal so taking place in the operator's telephones that the result, mathematically speaking, would be the same as if only one antenna had been used.

In Letters Patent No. 1,669,219, issued May 50 8, 1928, to Albert H. Taylor, another system

was described in which two receivers are provided with two heterodynes bringing the signals to different audible frequencies which can therefore be combined by means of a differential transformer. This later system has the disadvantage of requiring filters to take up the resulting beat frequency between the two heterodynes, which will be within audible beat frequency of each other. The two previously described systems have in each of them certain disadvantages, although both systems assist in the reduction of fading effects.

The receiving system of our invention permits the two signals, from the two collectors differently situated and spaced, to be received simultaneously. The receiving system of our invention also eliminates the objectionable beat notes which require filters between the two heterodynes to eliminate these beats. The present receiving system of our invention is an improvement on either of the other systems referred to. Better results are accomplished in our present system by employing in combination the differential transformer and two specially arranged superheterodyne receivers which are operated in a special manner with regard to the choice of the transfer frequencies.

The system can be understood by detailed reference to the drawings. Fig. 1 shows an arrangement of the superheterodyne receiver for continuous wave reception but which will work equally well for reception of modulated signals by preventing oscillations of the second detector. The receiving system of our invention operates both with continuous wave signals and also in the reception of modulated signals of voice frequencies. The superheterodyne circuit arrangement includes a first detector 1 whose frequency characteristics correspond to the frequency of the incoming signal. By means of a heterodyne or driver 2 having frequency characteristics differing from the incoming signal and loosely coupled to detector 1, the signal is transferred at a different and lower frequency through an amplifier and transfer circuit 3 and delivered to a second detector 4 which has frequency characteristics corre-

sponding to the frequency characteristics of the amplifier and transfer circuits 3. Second detector 4 in turn delivers the energy from its output circuit to the telephones 5 or audio frequency amplifier circuits.

- Referring to Fig. 2 let us suppose that collector A is differently arranged in space relationship to collector B so as to have a different time period of fading, due to selecting a slightly different portion of the wave front, or due to the two collectors being differently affected by different polarization of the wave front. As an illustration, collectors A and B may be antennas positioned in an east and west plane running in opposite directions and separated by a distance of about 100 meters. The centers of exposure of these antennas would therefore be 100 meters apart. These particular collectors would respond similarly to varying states of polarization but each one would operate upon a slightly different portion of the down-coming waves. In the case of frequency characteristics between 12,000 and 22,000 kilocycles, there would be several wave lengths between the centers of exposure of the two systems. However, this effect in the reduction of fading begins with much less separation between the centers of exposure. As another illustration, antennas A and B may be in the same horizontal plane and at right angles to each other. Antennas A and B would not only have different centers of exposure but respond to different polarization planes. A variety of combinations may be used effectively, some combinations working well at certain frequencies and on certain signals and others being preferable for other frequencies from other directions.
- If two identical superheterodynes marked Super Het A and Super Het B are used in the arrangement shown in Fig. 2 it will not be possible to get the desired results. In the first place, if the transfer frequencies are the same the oscillations of the two second detectors will produce an audible beat and unless very carefully filtered will interfere with each other. The filtering of these oscillations is not impossible but is rendered more difficult by the fact that the two output circuits are interconnected through the common differential transformers. Further, the two beating heterodynes which transfer the signal from its original high frequency form to the intermediate transfer frequency will have to be absolutely synchronized or they will produce audible beat frequencies. This is extremely difficult when the frequencies are in the order of 12,000 kilocycles or higher. Finally, if the oscillators and heterodynes are synchronized vector additions of the receiving signals will occur instead of arithmetic additions and the effect will be the same as though one superheterodyne had been used and the two

collectors combined on entering the superheterodyne receiver. This means that no material reduction in fading would result. It is obvious therefore, that if two identical superheterodynes were used the system would lack advantages, but by combining two separate superheterodynes having unlike characteristics, a reduction in fading phenomena on these higher frequencies is possible.

The first step is to cause the beating heterodyne frequencies to differ by an amount sufficient to cause the resultant beating frequency to be above the range of audibility. Any frequency difference above 10 kilocycles between the two beating heterodynes will suffice to meet this condition but too great a separation should not occur. When the two heterodynes, for instance, are caused to differ by 500 kilocycles, which is quite possible in the reception of signals having frequencies of the order of 20,000 kilocycles, the 20th harmonic of the two heterodynes causes a beat frequency in the signalling range. With weak signals this beat frequency might be strong enough to cause objectionable interference. By employing beat differences between the two heterodynes of the order of 10 to 50 kilocycles a very high order of harmonics would be required to cause beat frequencies within the signal range, and such beat frequencies are so weak as to be entirely negligible. As an illustration, suppose we choose the difference between the two beating heterodyne frequencies 20 kilocycles. This means in turn, that the transfer frequencies of the two heterodynes will differ by 20 kilocycles. There is a wide variety possible in the choice of these transfer frequencies and the above frequency is merely an illustration. It is convenient to choose the transfer frequency for superheterodyne A approximately 100 kilocycles and for superheterodyne B, in the example cited, 120 kilocycles. The signal from collector A is therefore transferred to oscillating second detector 1 at a frequency of 100 kilocycles where the audio frequency signal is produced by oscillating second detector 1 which may have a frequency difference of 800 kilocycles. The signal from collector B is transferred to superheterodyne B at a frequency of 120 kilocycles, requiring for an audible beat that the second detector of superheterodyne 2 be oscillated at a frequency of 120 kilocycles $\pm$ an audible frequency. We can cause the second audible frequency to be identical with the first one if we desire to do so, but if such is the case vector addition of the signals would result and not reduction of fading. A reduction of fading is possible however if we cause the audible beat frequencies to be different, one 800 cycles and the other 1200 cycles. Suppose that the incoming signal has a frequency value of

20,000 kilocycles. Both first detector circuits for superheterodynes A and B are tuned to this frequency value. The beating heterodyne for the superheterodyne A is adjusted to a frequency value of 20,100 kilocycles. The beating heterodyne for superheterodyne B is adjusted to a frequency value of 20,120 kilocycles. Under these conditions no beat frequencies between these two heterodyne frequencies are of sufficient strength to cause noticeable interference with reception. The oscillating second detector of superheterodyne A is adjusted to a frequency value of 100.8 kilocycles; the oscillating second detector of superheterodyne B is adjusted to a frequency value of 121.2 kilocycles. There is therefore no interfering beat frequency caused by the two oscillating second detectors. As shown in Fig. 2, the output of superheterodynes A and B is connected to transformer 6 by means of primary windings 7 and 8. Secondary winding 9 is connected to telephones 5 or may be connected to other audio amplifiers. Transformer 6 need not be of the differential type as any three winding transformer with suitable impedance ratio will give satisfactory results. Since the two signals can be brought in at two different audio frequencies and adjusted to cause a harmonious chord not annoying to the operator, the action of the fading, which is different on the two collectors, is emphasized alternately on the upper or the lower audio frequencies of the two.

35 The schematic circuit diagram of the receiving system of our invention is illustrated more in detail in Fig. 3. Two complete receiving systems A and B are illustrated. In receiver A, a radio frequency energy collector or antenna 27 transfers the incoming signal energy to the input circuit 28 of regenerative detector 12. A source of high frequency energy 11 is coupled to input circuit 28 of thermionic vacuum tube detector 12. The beat frequency caused by the source of high frequency oscillations and the source of incoming signalling energy, is amplified by thermionic vacuum tube 13, amplifier 14 and amplifier-detector 15. The second detector 15 which is an oscillating detector is adjusted to a frequency value whereby an audible beat frequency is produced. The audio beat frequency is amplified by amplifier 16 and reproduced in circuits 7, 9 and 5. In receiver B a radio frequency energy collector or antenna 29 transfers the incoming signal energy to the input circuit 30 of regenerative first detector 18. A source of high frequency energy 17 is coupled to input circuit 30 of thermionic vacuum tube detector 18. The source of incoming high frequency energy has a frequency value corresponding to the frequency value of the energy collected by antenna 27 and transferred to input circuit 28. Input circuit 30 is ad-

justed to a frequency value corresponding to the frequency value of input circuit 28. A source of high frequency energy 17, having frequency characteristics unlike source 11, is coupled to input circuit 30. The beat frequency energy, caused by the incoming signal and locally generated high frequency energy, is amplified by thermionic vacuum tube 19, amplifier 20 and amplifier-detector 21. The second detector 21 which is an oscillating detector, is adjusted to a frequency value whereby an audible beat frequency is produced. This audible beat frequency is of a value differing from that produced in amplifier and second detector 15 of receiver A. The audio beat frequency is amplified by amplifier 22 and reproduced in circuits 8, 9 and 5. Circuits 9 and 5 are common to the output of amplifiers 16 and 22. There will therefore be beat frequencies of two different frequency values in circuits 9 and 5. Sources of potential 25, 26, 23 and 24 are illustrated as batteries. It is obvious that any suitable supply may be employed. Thermionic vacuum tubes 13 and 19 are illustrated as of the shielding plate type, although it is also obvious that three electrode tubes may be employed. We realize that many modifications of our invention are possible without departing from the spirit of our invention and it is to be understood that our invention is not to be restricted by the foregoing specification or the accompanying drawings but only as defined in the scope of the appended claims.

What we claim as new and desire to secure by Letters Patent of the United States is as follows:

1. A radio receiving system comprising in combination independent radio frequency energy collecting circuits, independent receiving circuits connected to said collecting circuits, a plurality of independent high frequency generators each having frequency characteristics differing from the other by a super-audible frequency, each of said receiving circuits being adapted to heterodyne with at least one of said high frequency generators to produce super-audible beat frequencies and reproducing means common to each of said last mentioned circuits.

2. The method of receiving wireless signals with geographically separated antennæ which consists in receiving the same signal upon each of a pair of said antennæ to produce a pair of signal effects, independently heterodyning each of said signal effects to produce an intermediate frequency differing from that of the other, fixing the frequencies with which said signal effects are heterodyned so that the propagation of an audible beat frequency therebetween is avoided, independently amplifying and detecting each of said intermediate frequencies to produce an audio frequency differing from that of the other.

and combining said audio frequencies, whereby the effects of fading are substantially reduced.

3. An apparatus for the elimination of fading comprising a plurality of spaced antennæ each adapted to receive the same signal effect, an independent heterodyne receiving network connecting respectively with each of said antennæ, means associated with each of said receiving networks to produce an intermediate frequency different from that of the other, said means being so related to one another in the respective networks as to avoid the direct propagation of an audible beat note therebetween, means included in each receiving network to independently amplify and detect each said intermediate frequency so as to produce an audio frequency in one said network different from that of the other, means for combining said audio frequencies to produce a composite signal effect, and reproducing means responsive to said composite signal effect.

4. The method of receiving wireless signals in a combining circuit with geographically separated antennæ which consists in receiving the same signal upon each of a plurality of said antennæ and producing a plurality of signal effects thereon, directing the energy from each of said antennæ to separate receiving systems, producing a super-audible beat frequency different in character in each of said systems while avoiding the propagation of an audio-frequency beat note as between the oscillatory characteristics of the respective systems by maintaining a super-audible frequency difference between the respective beat frequencies, separately amplifying the beat frequency produced in each of said systems, separately detecting the separate beat frequencies, and producing separate audio frequencies in said receivers and combining the separate audio frequencies in the combining circuit whereby the effects of fading are substantially eliminated.

5. An apparatus for the elimination of fading comprising a plurality of antennæ each having different instantaneous fading characteristics, a separate superheterodyne receiver coupled to each of said antennæ, means for producing different output frequencies from said receivers for the same received signal, said means including oscillators the frequencies of which are so fixed as to avoid audio-beat-frequency heterodyning with one another, independent selective intermediate frequency amplifiers in each receiver, a rectifier coupled with the output of each said intermediate frequency amplifier, a common receiving instrumentality coupled to the output circuits of said rectifiers, whereby signals received upon said antennæ are received in said receiving instrumentality substantially unaffected by fading and are combined into an harmonious chord of audio frequencies.

6. An apparatus for the elimination of fading comprising a plurality of geographically spaced antennæ each having different instantaneous fading characteristics and adapted each to receive the same signal energy, a separate receiver connected with each said antenna, means for producing a different radio frequency heterodyne beat note on the same signal with each receiver, said means including oscillators the frequencies of which are so fixed as to avoid audio-beat-frequency heterodyning with one another, a selective radio frequency amplifier associated with the output of each of said receivers for amplifying the separate beat frequencies, a separate detector connected with the output of each said amplifier and a receiving instrumentality for combining in one output circuit the audio frequencies resulting from rectification by said rectifiers whereby signals received upon said geographically spaced antennæ have their energies added and combined in said receiving instrumentality and the effects of fading substantially eliminated.

7. A method of reducing fading effects which comprises receiving radio signaling waves of relatively high frequency at separated places, combining said waves received at said places with combining waves of frequencies different from that of the received waves to produce intermediate frequency waves of frequency lower than that of said received waves, said combining waves being so related to one another as to avoid the propagation of an audio frequency beat note therebetween, the frequencies of said combining waves being different at different ones of said places whereby different intermediate frequencies result from said combining actions, separately detecting the signal component of each said combining resultant wave and producing a relatively low frequency signal current in each of a plurality of receiving systems and adding said waves of low frequency to produce an audible signaling chord.

In testimony whereof we affix our signatures.

ALBERT H. TAYLOR.
LEO C. YOUNG.
